(57) CLAIM

The ornamental design for a digital video disk player, as shown and described.

DESCRIPTION

FIG. 1 is a perspective view of a digital video disk player showing our new design;

FIG. 2 is a front view thereof;

FIG. 3 is a rear view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, wherein the display cover is in the open position. Inside portion in broken lines is for illustrative purpose only and forms no part of claimed design.

1 Claim, 6 Drawing Sheets
